(57) **CLAIM**

An ornamental design for a syringe cap as shown and described.

DESCRIPTION

FIG. 1 is a perspective view of a syringe cap showing the claimed design;

FIG. 2 is a front view thereof;

FIG. 3 is a rear view thereof;

FIG. 4 is a top plan view thereof, the bottom plan view being the same;

FIG. 5 is a right side view thereof;

FIG. 6 is a left side view thereof;

FIG. 7 is a cross-sectional view taken along line VII-VII in FIG. 2;

FIG. 8 is a cross-sectional view taken along line VIII-VIII in FIG. 4; and,

FIG. 9 is a reference view showing an actual use of the syringe cap on a syringe.

The broken lines in the drawings depict portions of the syringe cap that form no part of the claimed design.

1 Claim, 5 Drawing Sheets
